UNITED STATES PATENT OFFICE.

ALOIS HELFENSTEIN, OF VIENNA, AUSTRIA-HUNGARY.

ELECTRIC FURNACE.

1,002,843.

Specification of Letters Patent. Patented Sept. 12, 1911.

Application filed November 16, 1909, Serial No. 528,362. Renewed July 26, 1911. Serial No. 640,694.

To all whom it may concern:

Be it known that I, ALOIS HELFENSTEIN, a citizen of the Republic of Switzerland, and residing at Vienna, in the Empire of Austria-Hungary, have invented certain new and useful Improvements in Electric Furnaces, of which the following is a specification.

Electric furnaces having a plurality of shafts which form melting hearths, the bottom electrodes of which are connected by conducting means such as wires or cables are known. (See the German Patent No. 190425.) This construction requires the conductors to be placed on the outside of the furnace and causes damage of the conductors owing to the heat of the furnace.

The object of the present invention is to provide a system of furnaces having a common bottom electrode, that is, a single massive body serves as a common bottom to all of the furnaces and serves for the conducting of the electric current between the various furnaces; upon this massive conducting body single furnace shafts are constructed whereby each single shaft may be used as an independent working hearth so that it is possible to conduct melting operations of different characters in the different furnaces and different products may be obtained while all of the separate shafts are working, although all of the shafts have but one common bottom electrode.

The furnace system constituting the present invention is shown diagrammatically in the accompanying drawings, in which like numerals designate like parts throughout the several figures.

Referring particularly to the drawings:—
40 Figure 1 represents a vertical longitudinal section of half of the furnace system, three shafts being shown; Fig. 2 is a horizontal section of the same taken below the line A—A of Fig. 1; Fig. 3 represents a section taken on the line B—B of Fig. 1; Fig. 4 represents a section showing a single shaft and the flue, the same being taken on the line C—C of Fig. 2; Fig. 5 represents a top plan view of the furnace system.

50 In the drawings I have represented a furnace system consisting of six distinct shafts each being adapted to operate as a working hearth, and all having a common bottom electrode, but I wish it distinctly understood that I do not limit myself to the arrangement shown, as any arrangement consisting

of a plurality of independent working hearths all having a common bottom electrode lies within the scope of the present invention.

Referring particularly to the drawings: a¹, a², a³, a⁴, a⁵, and a⁶ represent the six furnace shafts each being, as before stated, adapted to operate as an independent working hearth and in which melting operations of different characters may be carried out. Each of the shafts is provided with side walls b, and the furnace system has a common bottom structure T, as shown. Each furnace shaft is provided with a charging opening c, and into each shaft plunges an electrode e. The furnaces are preferably arranged as shown, that is in two parallel rows of three furnaces each, the two rows being separated by a longitudinally disposed flue chamber f arranged in parallelism with each row of furnace shafts. The flue chamber is connected with each of the furnace shafts by means of passages f, so that the gases generated in the various shafts during the electric melting operations may pass to the flue chamber f and find a common outlet. A brick work or other masonry structure g, the walls of which form one side of each of the furnace shafts, is also disposed between the two rows of furnace shafts, the brick work g being shown in Fig. 4. Placed upon the bottom T of the furnace structure is a massive electric conducting body D, the same serving as a bottom electrode common to all of the furnace shafts described.

The conducting body D consists in general of a rectangular-shaped mass of conducting material having lateral extensions which enter the various furnace shafts. As will be seen upon reference to the drawings, the conducting body D does not serve as a means of communication of the molten material reduced in the furnace shafts so that the molten material could pass from one shaft to the other, but in conducting melting operations according to the system described, each furnace shaft is operated as an independent melting hearth, and the molten products may be drawn off independently from the various furnace shafts.

In practice when it is desired to conduct a melting operation, each of the shafts either containing the same kind of material, or several of the shafts containing one kind of material and the remaining shafts a different kind, the electrodes e will be lowered

in the known manner and the current will travel from the said electrodes into the common conducting electrode D, the gases generated during the operations escaping through the flue chamber f. As the operation continues and the molten material accumulates the electrodes E will be raised in the known manner. The final molten product may be drawn off independently from each of the furnace shafts.

A damper h serves to regulate the flue passages f', as shown.

I claim:

1. In an electric furnace, a plurality of 15 separate shafts, each shaft being adapted to work as an independent melting hearth, an electrode disposed in each shaft, and a single bottom electrode serving as common bottom electrode for all of the shafts.
2. In an electric furnace, a plurality of 20 separate shafts, each being adapted to work as an independent melting hearth, an upper vertical electrode disposed in each shaft, and a conducting body arranged horizontally in 25 the lower part of the furnace, said body serving as a common bottom electrode for all of said shafts.
3. In an electric furnace, a plurality of 30 shafts, each shaft being adapted to work as an independent melting hearth, an upper electrode disposed in each of said shafts, and a conducting body arranged beneath said shafts in such a manner as to close communication between the lower parts of the 35 several shafts, said conducting body serving as a common bottom electrode for all of the shafts.
4. In an electric furnace, two rows of 40 vertical shafts each of said shafts being adapted to work as an independent melting hearth, an upper electrode disposed in each of said

shafts, a flue chamber arranged between said two rows of shafts, passages connecting said flue chamber with each of said shafts, and a conducting body arranged in the lower 45 part of said furnace, said conducting body serving as common bottom electrode for all of said shafts.

5. A furnace structure comprising a plurality of shafts, each shaft being adapted to 50 work as an independent melting hearth, a flue chamber, passages connecting said flue chamber with each of said shafts, an upper electrode arranged in each of said shafts, and a conducting body arranged in the 55 lower part of said furnace structure and beneath said shafts in such a manner as to close communication between the lower parts of said shafts, said conducting body serving as common bottom electrode for all of said 60 shafts.

6. A furnace structure comprising two rows of vertical shafts, each shaft being adapted to work as an independent melting hearth, a vertical upper electrode disposed 65 within each of said shafts, a flue chamber arranged between said rows of furnace shafts, passages connecting said flue chamber with each of said vertical shafts, and a conducting body horizontally arranged in 70 the bottom of said furnace structure in such a manner that a portion of its body lies beneath each of said vertical shafts, said conducting body serving as common bottom electrode for all of said shafts.

In testimony whereof I affix my signature in presence of two witnesses.

ALOIS HELFENSTEIN.
